Primary Examiner — Ian Simmons*Assistant Examiner* — Keith Frank(74) *Attorney, Agent, or Firm* — Adam K. Sacharoff; Much Shelist(57) **CLAIM**

The ornamental design for a ribbed container, as shown and described.

DESCRIPTION

FIG. 1 is a front side perspective view showing a first embodiment of the new design for a ribbed container; FIG. 2 is another front side perspective view of the ribbed container from FIG. 1;

FIG. 3 is a bottom rear side perspective view of the ribbed container from FIG. 1 in an upside down configuration; FIG. 4 is a front elevation view of the ribbed container from FIG. 1;

FIG. 5 is a rear elevation view of the ribbed container from FIG. 1;

FIG. 6 is a left side view of the ribbed container from FIG. 1;

FIG. 7 is a right side view of the ribbed container from FIG. 1;

FIG. 8 is a top plan view of the ribbed container from FIG. 1;

FIG. 9 is a bottom plan view of the ribbed container from FIG. 1;

(Continued)

FIG. 10 is a front side perspective view showing a second embodiment of the new design for a ribbed container;
FIG. 11 is a rear side perspective view of the ribbed container from FIG. 10;
FIG. 12 is a bottom rear side perspective view of the ribbed container from FIG. 10 in an upside down configuration;
FIG. 13 is a front elevation view of the ribbed container from FIG. 10;
FIG. 14 is a rear elevation view of the ribbed container from FIG. 10;
FIG. 15 is a left side view of the ribbed container from FIG. 10;
FIG. 16 is a right side view of the ribbed container from FIG. 10;
FIG. 17 is a top plan view of the ribbed container from FIG. 10;
FIG. 18 is a bottom plan view of the ribbed container from FIG. 10;
FIG. 19 is a front side perspective view showing a third embodiment of the new design for a ribbed container;
FIG. 20 is a rear side perspective view of the ribbed container from FIG. 19;
FIG. 21 is a bottom rear side perspective view of the ribbed container from FIG. 19 in an upside down configuration;
FIG. 22 is a front elevation view of the ribbed container from FIG. 19;
FIG. 23 is a rear elevation view of the ribbed container from FIG. 19;

FIG. 24 is a left side view of the ribbed container from FIG. 19;
FIG. 25 is a right side view of the ribbed container from FIG. 19;
FIG. 26 is a top plan view of the ribbed container from FIG. 19;
FIG. 27 is a bottom plan view of the ribbed container from FIG. 19;
FIG. 28 is a front side perspective view showing a fourth embodiment of the new design for a ribbed container;
FIG. 29 is a rear side perspective view of the ribbed container from FIG. 28;
FIG. 30 is a bottom rear side perspective view of the ribbed container from FIG. 28 in an upside down configuration;
FIG. 31 is a front elevation view of the ribbed container from FIG. 28;
FIG. 32 is a rear elevation view of the ribbed container from FIG. 28;
FIG. 33 is a left side view of the ribbed container from FIG. 28;
FIG. 34 is a right side view of the ribbed container from FIG. 28;
FIG. 35 is a top plan view of the ribbed container from FIG. 28; and,
FIG. 36 is a bottom plan view of the ribbed container from FIG. 28.
The broken lines are for environmental purposes only and form no part of the claimed design.
